(57) **CLAIM**

The ornamental design for a wire connector with hexagonal shape flange, as shown and described.

DESCRIPTION

FIG. 1 is a side view of the preferred wire connector of the present invention

FIG. 2 is a bottom perspective view of the wire connector of the present invention.

FIG. 3 is a top plan view of the wire connector of the present invention; and,

FIG. 4 is a bottom plan view of the wire connector of the present invention.

1 Claim, 3 Drawing Sheets

FIG. 1

FIG. 2

FIG. 3

FIG. 4
